C. M. HARRINGTON.

HAIRPIN.

APPLICATION FILED DEC. 10, 1919.

1,367,874.

Patented Feb. 8, 1921.

Inventor:
Clyde M. Harrington,
by *Charles O. Sherry*,
his Atty.

UNITED STATES PATENT OFFICE.

CLYDE M. HARRINGTON, OF CHICAGO, ILLINOIS, ASSIGNOR TO SAMUEL LOWITZ, OF CHICAGO, ILLINOIS.

HAIRPIN.

1,367,874.

Specification of Letters Patent.

Patented Feb. 8, 1921.

Application filed December 10, 1919. Serial No. 343,874.

To all whom it may concern:

Be it known that I, CLYDE M. HARRINGTON, a citizen of the United States, and a resident of Chicago, Cook county, and State 5 of Illinois, have invented certain new and useful Improvements in Hairpins, of which the following is declared to be a full, clear, and exact description.

This invention relates to hair pins, and its 10 principal object is to provide inherent means in the hair pin to automatically lock the same in the hair when in use, whereby any danger of the hair pin becoming accidentally loosened, and falling out is entirely avoided. 15 Many attempts have been made to overcome this difficulty, with more or less success. With the use of the present invention, self locking hair pins may be constructed without adding any appreciable amount to the 20 cost of manufacture. They are highly efficient, and are handled or used in the familiar manner.

With these and other objects and advantages in view, this invention consists in 25 the several novel features hereinafter fully described and claimed.

The invention is clearly illustrated in the drawing accompanying this specification, in which:—

30 Figure 1 is a side elevation of a hair pin embodying a simple form of the present invention; Fig. 2 is an edge view thereof looking in the direction of the arrow 2 in Fig. 1; Fig. 3 is a detail cross section taken on line 3—3 of Fig. 1, and Fig. 4 is a detail cross section taken on line 4—4 of Fig. 1.

Referring to said drawing, which illustrates a simple embodiment of the present invention, the reference characters 3, 4, 40 designate the two legs of the hair pin, which extend from a U bend 5, as is usual in hair pins, and preferably, although not necessarily so, said legs diverge slightly toward their free ends; said legs are preferably 45 straight throughout the greater portion of their length, but adjacent the bent end they are crimped as will be hereinafter set forth, to provide the locking means therefor, and it is the peculiar formation of this crimped 50 portion of the legs that provides the highly efficient locking means for the pin.

Generally speaking both legs 3, 4, are bent to form opposite zig zag portions near the U bend (see Fig. 1) and the opposite members of the zig zag portions are also bent in

opposite directions from the plane of the pin to give them a sort of zig zag shape (see Fig. 2), the zig zag lines of one leg opposing the zig zag lines of the other and forming wedge like structures that define wedge like 60 openings when viewed as seen in Fig. 2.

Referring now to Fig. 1, the portions 6, 6^a of the legs are straight; at 7, the leg 3 is bent forward and at 7^a the leg 4 bent backward to provide short bent portions 8, 8^a both of 65 which, however, are carried toward the median line between the legs, so that they lie in two parallel planes extending in a direction oblique to the general plane of the pin (see Fig. 3). The short bent portions 70 8, 8^a are bent at 9, 9^a to form portions 10, 10^a, the portion 10 of the leg 3 being bent backward and the portion 10^a of the leg 4 being bent forward, and both being bent outward from the median line to form diverging portions 75 when viewed as seen in Fig. 1. The bent portions 10, 10^a are somewhat longer than the bent portions 8, 8^a, and extend at a less oblique angle than said portions 8, 8^a and at the places where they intersect, the 80 plane of the pin (see Fig. 2) the part 10 is bent back and the part 10^a is bent forward at 11, 11^a, to form abrupt portions 12, 12^a both being bent toward the median line between the legs and both lying in parallel planes 85 (see Fig. 4). The portions 12, 12^a are comparatively short and extend about as far to one side of the plane of the pin as the portions 8, 8^a, extend on the other side thereof. At 13, the portion 12^a is bent forward and 90 at 13^a the portion 12^a bent backward as at 14, 14^a both being bent outwardly so as to diverge from each other, and both merging 95 into the straight portions of the legs 3, 4 as at 15, 15^a.

By reference to Fig. 2 it will be seen that the portions 6, 6^a, of the legs are straight; that the portions 8, 8^a are bent oppositely, and abruptly away from the plane of the pin, and bent back to the plane of the pin at 100 10, 10^a, to leave therebetween, an opening 16, (when the pin is viewed toward its edge); that the portions 10, 10^a intersect the plane of the pin at 11 and thereat are bent in opposite directions as at 12, 12^a, and then bent back to the plane of the pin as at 14, 14^a 105 where they merge into the straight portions at 15, 15^a leaving an opening 17 between them.

It will also be noted that the portions 10, 110

10^a, and 14, 14^a, when viewed as seen in Fig. 2, converge toward each other from top to bottom, thereby producing the wedge shaped openings 16, 17, having wedge shaped sides. 5 The result is that when the hairpin is thrust among the strands of hair, bunches of the strands are caught above the abrupt portions 8, 8^a and in openings 16, 17, between the converging portions, 10, 10^a, and 14, 14^a, of the legs and become wedged against said legs thereby preventing the hair pin from being withdrawn except upon the application of sufficient force to bend the strands of hair back far enough for the protruding bent 10 ends to pass, or the hair must be bent far enough to pass out through the gaps between the corners 9, 9^a, and 13, 13^a of the oblique portions.

The hair pin is inserted among the hair as 20 is customary in use. Some of the strands of hair lie on one side of one leg and some on the other side of the other leg, and as the crimped end of the hair pin is pushed into the hair, the strands of hair enter the 25 spaces between the oblique portions 14, 14^a, and 10, 10^a, and above the portions 8, 8^a, and are effectively held in the openings 15, 17 by the oblique crimped portions.

The hair extends across the abrupt portions, 8, 8^a, and 12, 12^a, which resist any slight effort to withdraw the pin from the hair, but when the pin is rotated or turned slightly back and forth, and the gaps between the corners 9, 9^a, and 13, 13^a brought 35 across the strands of hair, the pin can be easily withdrawn. It will be noted that the hair holds the long straight portions of the pin from turning about the axis of the pin except when force is applied to the other 40 end. On account of the comparatively long sloping portions 14, 14^a, and 10, 10^a, the pin may be easily and readily inserted in the hair, and on account of the abrupt portions 12, 12^a, and 8, 8^a considerable force or other manipulation of the pin must be had to retract it from the hair.

One important difference between a hair

pin containing the present invention, and those heretofore used is that friction is not depended on to secure the pin in place, but 50 it is locked in the hair by the abrupt shoulders crossing the hair held by the pin. Moreover, the hair need not be crowded in between the two members of the pin as is customary with hair pins having zig zag 55 bends to obtain the locking effect, and thus the usual uncomfortable feeling resulting from the use of such hair pins is eliminated.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure my Letters Patent:

1. A hair pin comprising two members, united at one end and free at the other, said 70 members having oppositely crimped zigzag portions bent in reverse directions from the main plane of the pin to lie in planes, oblique thereto.

2. A hair pin comprising two members 75 united at one end and free at the other, said members having oppositely crimped zigzag portions, each consisting of an abruptly bent short part and a more inclined long part, the opposing portions being bent 80 in reverse directions from the main plane of the pin to lie in planes, oblique thereto.

3. A hair pin comprising two members, united at one end and free at the other, said 85 members having oppositely crimped zigzag portions, each zigzag bend consisting of an abruptly bent short part and a more inclined long part, the opposing portions being bent in reverse directions from the main plane of the pin to lie in planes, oblique 90 thereto, and the zigzag bends on each member running in reverse directions from the main plane of the pin.

CLYDE M. HARRINGTON
